UNITED STATES PATENT OFFICE

109,616

DESIGN FOR A COMBINED ASHTRAY, PIPE KNOCKER, AND PIPE RACK

Edward F. McDonald, Buffalo, N. Y.

Application November 23, 1937, Serial No. 73,133

Term of patent 14 years

To all whom it may concern:

Be it known that I, Edward F. McDonald, a citizen of the United States, residing at Buffalo, in the county of Erie and State of New York, have invented a new, original, and ornamental Design for a Combined Ashtray, Pipe Knocker and Pipe Rack, of which the following is a specification, reference being had to the accompanying drawing, forming part thereof.

The figure is a perspective view of a combined ashtray, pipe knocker, and pipe rack, showing my new design.

I claim:

The ornamental design for a combined ashtray, pipe knocker, and pipe rack, as shown.

EDWARD F. McDONALD.
